CLAIM

We claim the ornamental design for a granulated product dispenser, as shown and described.

DESCRIPTION

FIG. 1 is a top front right perspective view of a granulated product dispenser showing our new design;
FIG. 2 is a front elevation view thereof;
FIG. 3 is a rear elevation view thereof;
FIG. 4 is a left side elevation view thereof;
FIG. 5 is a right side elevation view thereof;
FIG. 6 is a top plan view thereof; and,
FIG. 7 is a bottom plan view thereof.

The short dash, short dash broken lines in FIGS. 1, 6, and 7 represent portions of the granulated product dispenser that form no part of the claimed design. The long dash, short dash broken lines and area within in FIG. 2 define the bounds of the claimed design and form no part of the claimed design.
